UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

THREAD-CONTROLLER FOR SEWING-MACHINES.

1,129,588.

Specification of Letters Patent.

Patented Feb. 23, 1915.

Application filed September 10, 1907. Serial No. 892,205.

To all whom it may concern:

Be it known that I, LANSING ONDERDONK, a citizen of the United States, residing at New York city, in the county of New York, State of New York, have invented certain new and useful Improvements in Thread-Controllers for Sewing-Machines, of which the following is a description, reference being had to the accompanying drawing, and 10 to the letters and figures of reference marked thereon.

My invention relates to new and useful improvements in thread controllers for sewing machines, and while said thread controller may be used in various relations to the stitch forming elements of a sewing machine, the same is more especially adapted for use in connection with the needle thread of a machine of this character.

20 The object of my invention is to provide a thread controller which will operate on the needle thread as the needle starts on its downward movement to take up the slack in front of the needle so as to prevent the 25 thread buckling or doubling upon itself in front of the point of the needle.

A further object of my invention is to provide a thread controller which shall operate to pull upon the thread after the 30 needle loop is shed from the looper in order that the thread controller may assist the needle in running up the previous needle loop dropped from the looper, close to the under surface of the work.

35 A still further object of my invention is to provide a thread controller which shall operate upon the needle thread during the first movements of the needle as the same starts on its upward stroke whereby the 40 needle thread is not only carried up with the needle so as to prevent the forming of a double loop, but also to pull a little of the thread through the eye of the needle at this time and thus reduce the size of the needle 45 loop, which would otherwise be thrown out by the needle.

A still further object of my invention is to provide a needle thread controller which shall operate to control the needle thread at 50 the proper time throughout the formation of the stitch, so that a tight stitch may be formed regardless of the thickness of the work operated upon.

Still further objects of my invention, will

in part be obvious, and will in part be more 55 fully hereinafter described.

My invention consists in the parts, improvements and arrangements hereinafter shown and described, and set forth in the 60 claims.

In the drawings which show by way of illustration one embodiment of my invention: Figure 1 is a front elevation, partly in section and with parts removed, showing a sewing machine with my improvements applied thereto. Fig. 2 is a detail in front elevation of the needle head with certain parts removed for the sake of clearness and showing in dotted lines the movements of the thread controlling arms. Fig. 3 is a 70 diagrammatic view showing the position of the thread arm relative to the thread guides when the needle is at its lowest points of movement. Fig. 4 is a view similar to Fig. 3, with the needle in the middle of its upward stroke. Fig. 5 is a similar view with the needle at the upper extreme of its stroke. Fig. 6 is a similar view with the needle in the middle of its downward stroke. Fig. 7 is a detail view in front plan showing a 80 modified form of my invention. Fig. 8 is a similar view of another modified form of my invention. Fig. 9 is a detail view showing the adjustable thread guide which is located between the thread controlling arms. 85 Fig. 10 is a detail in section, showing the manner of adjustably supporting the post carrying the thread controlling arm.

In the drawings the bed plate 1 has rising therefrom a standard 2 which carries an 90 overhanging arm supporting at the outer end, a needle head 3. Said needle head 3 is provided with a needle bar 4 carrying a needle 5, secured to the needle bar by the needle clamping collar 6. Said needle 95 receives its reciprocation from the main shaft 7 which is mounted in the overhanging arm and continuously rotated from any suitable means. Said main shaft 7 carries the usual crank disk 8 on its forward end, which is connected by a link 9 to a collar 10 on the needle bar.

The presser bar 11 is mounted in the needle head, and carries a presser foot 12 at the lower end. Said presser bar is lifted by 105 the usual hand lever 12^a. Said presser bar carries a collar 13 which is rigidly secured thereto and a suitable spring 14 mounted on

the head of said machine, engages said collar 13 and thereby holds the presser foot in contact with the work support.

A thread controlling arm 15 is pivoted to an arm 16 which is formed integral with a suitable bracket 17 upon the head of the machine. Said bracket 17 is adjustably mounted in the head of the machine in any suitable manner. The thread controlling arm 15 is provided with a thread eye 18 at its forward end and is pivotally connected by means of a link 20 to the collar 13 upon the presser bar at its rear end.

It will be obvious that as the presser bar 15 is raised and lowered by varying thicknesses of material, that the thread eye 18 in the forward end of the thread controlling arm 15 will also be lowered and raised. The needle bar is provided with a thread guide 21 at its upper end, and with a thread guide 22 which is preferably secured to the needle clamping collar 6, at the lower end of the needle bar.

My improved thread controller in the present embodiment of my invention consists of an arm 23, which is preferably rigidly secured to the needle bar operating link 9. Said arm projects outwardly from said link substantially at right angles to the longitudinal axis thereof, and to a point outside of the needle head casing. The outer end of said arm 23 is provided with suitable spaced lips 24 between which is mounted the thread engaging arms 25 and 26. Said thread engaging arms 25 and 26 as shown in the drawing, are formed integral and secured to the arm 23 by a screw 27. The thread arm 25 is provided at its outer end with a thread guide 28 which may be formed by bending the end of the arm into an open eye as shown in the drawings or may be formed by notching the outer end of said arm or in any other suitable way. The thread arm 26 is provided with a similar thread guide 29.

Mounted on the front face plate 30 of the machine, is a stationary thread guide 31 (see Figs. 1 and 9). Said thread guide 31 is preferably formed with a slotted shank 32 and is secured by a suitable screw 33 to said face plate. The stationary thread guide 31 is mounted at one side of the path of movement of the thread arm 26. Said thread guide is preferably provided with an open end so that the thread may be inserted therein. By loosening the screw 33, said thread guide may be adjusted up or down so that the relative position of said guide to the thread guides 28 and 29 may be varied.

Cooperating with the thread carrying needle 5, is a thread carrying looper 34 (see Fig. 1). Said looper 34 is mounted upon a suitable carrier 35, which is oscillated by a link 36 connected to a rock lever 37, which in turn is connected by a link 38 to a crank

39, mounted upon the shaft 40 in the bed of the machine, which is continuously rotated from the main shaft 7 in the overhanging arm. Said looper mechanism forms no part of the present invention but is shown, described and claimed in my application Serial No. 392,207 filed of even date herewith.

In Fig. 7 of the drawing, I have shown a thread eye 41, secured to the thread arm 26 in place of the stationary thread guide disclosed in Figs. 1 to 6 of the drawing. With the thread guide mounted upon the arm 26, the control of the needle thread is similar in character to that shown in Figs. 1 to 6, although the amount of thread taken up and released by the thread guides 28 and 29 in their movement is slightly different.

In Fig. 8 of the drawing, I have shown a single thread arm 42 which is secured to an offset 43 formed on the link 9, which operates the needle bar. Said thread arm 42 is provided with an open thread eye 44. A stationary thread guide 45 is secured to the head of the machine. By this form of construction, the thread controlling arm 42, 90 operates practically in the same manner as the thread controlling arm shown in Figs. 1 to 6, except that the thread by this construction is not taken upon the first downward movements of the needle as is done in 95 the other form of my invention.

The movements of the thread engaging arms 25 and 26 is clearly shown in Figs. 2 to 6 of the drawing. The full line position of the thread engaging arms A in Fig. 2 is 100 the same as that shown in Fig. 5. The dotted position B in Fig. 2 is the same as in Fig. 6 of the drawing. The dotted position C in Fig. 2 is the same as in Fig. 3 of the drawing. The dotted position D in 105 Fig. 2 is the same as in Fig. 4 of the drawing.

The operation of my device will be obvious from the above description. As the needle bar moves downward starting from 110 the position shown in Fig. 5, the thread eye 29 is moved outward and operates to take up the thread. At the same time the thread eye 28 moves inward releasing a slight amount of thread. The thread drawing 115 movements of the thread guide 29 however, exceed the thread releasing movements of the thread guide 28 and therefore, as the needle descends, the slack thread which would otherwise form in front of the needle 120 is drawn up and thus all liability of the needle thread buckling or doubling in front of the needle is avoided.

After the point of the needle has entered the looper thread loop, the previous needle 125 loop carried by the looper, is shed from the looper by backward movements thereof. Inasmuch as the needle eye is at this time beneath the surface of the work its further downward movement draws upon the needle 130

thread and the previous needle loop which is dropped from the looper, will be drawn up toward the under side of the work by the downward stroke of said needle. At this time in the movement of the needle the thread controlling arms are exerting a pull on the needle thread. The thread eye 29 in its first movement from the position shown in Fig. 6 moves substantially downward as the crank pin is substantially at a dwell in its horizontal movement at this time. This downward movement of the thread guide 29 continues until the crank operating the needle bar has passed through a considerable portion of the arc on its travel to the position shown in Fig. 3. This downward and slightly inward movement of the thread guide 29 during this period of the travel of the crank pin operating the needle bar causes the thread guide 29 to pull on the thread extending between the thread guide 21 and the fixed thread guide 31. During this same period the thread guide 28 is moved downward and outward away from the needle bar and the thread between the fixed guide 31 and the thread guide 22 is pulled on. The combined pulling movements of these thread guides during this period take up the needle thread as above noted. The needle reaches substantially the lower end of its stroke before the crank pin reaches the point where it rapidly moves horizontally which in turn moves the thread guide 29 rapidly toward the needle bar to the position shown in Fig. 3. This movement of the thread guide may possibly give up a little thread to the needle but the thread pulling movement of the needle for drawing up the previous needle loop shed from the looper has been assisted by the previous pulling on the thread by the thread guides 28 and 29 during the first part of the movement of the crank pin from the position shown in Fig. 6 to the position shown in Fig. 3. In order that a very tight stitch may be made, it is essential that this needle loop shall be run close up to the under surface of the material and by the present arrangement of parts, I am enabled to accomplish this running up of the needle loop to the position desired. Then again, if the needle loop is not run up close to the under surface of the work, it is liable to get into the way of the looper on its next forward movement and be entered by the same, thus, forming imperfect stitches and possibly breaking the thread.

As the needle bar begins its upward stroke, a loop of thread is thrown out for the entrance of the looper. If the slack thread on the supply side of the eye of the needle is not taken up with the needle, a double loop is formed which often results in the cutting or breaking of the thread. At this period in the movement of the needle bar, my thread controlling arms are moving relative to the thread guide 31, (see Fig. 4), so that a pull is exerted upon the needle thread thereof. This pulling movement of the thread controlling arms, operates to take up all slack in the needle thread on the supply side, formed by the upward movement of the needle. The movement of the thread arms at this time, is preferably such that not only the slack on the supply side of the needle eye is taken up, but also some of the thread is drawn through the needle eye, and the loop which would ordinarily be thrown out by the needle, is reduced in size. The looper mechanism co-operating with the needle to form the stitch, is preferably constructed so that a very small looper may be used and when a small looper having a short stroke is used, it is desired to throw out a small loop of needle thread, for if a larger loop than is absolutely necessary for the proper co-operation of the looper is formed, then the needle loop will not be properly held back upon the looper, and furthermore, the extra amount of thread in the larger loop will have to be drawn up in setting the stitch.

As the needle reaches the upward end of its stroke the thread guide 21 at the upper end thereof, will carry the thread into engagement with the thread eye or guide 18, on the thread controlling arm 15, and the movements of the thread guide on the needle bar above the thread eye on the thread controlling lever will place the final strain on the needle thread to set the stitch and draw from the supply the amount of thread necessary for the next stitch.

The thread eye 18 on the thread controlling lever is moved up or down according to the thickness of the material operated upon and therefore, the amount of thread drawn off, is regulated by the thickness of the material in which the stitch is to be formed.

By my improved thread controller, where in the needle thread is drawn through the eye of the needle, to pull up the previous needle loop when the needle is beneath the material, the position of the thread in the eye of the needle is constantly being changed, and, therefore, the strain on the needle thread due to pulling the same against the eye of the needle is less liable to break said needle thread.

Having thus described my invention, what I claim as new and desire to secure by Letters Patent, is:—

1. The combination of a needle, a looper, and a needle thread controller including a thread engaging device, thread guides co-operating with said thread engaging device, and means for moving said thread engaging device relative to said thread guides to take up the thread in front of the needle on the first part of the downward stroke of the

needle and for moving said thread engaging device relative to said thread guides to pull up the previously formed needle loop after the same is shed from the looper 5 and on the last part of the downward movement of said needle.

2. The combination of a needle, a looper, and a needle thread controller including a thread engaging device, thread guides co-10 operating therewith, and means for moving said thread engaging device relative to said thread guides to take up the slack in front of the needle on the first part of the downward movement thereof and to take up the 15 slack in the needle thread as the needle rises and for moving said thread engaging device relative to said guides, so that the same coöperates with the needle to draw up the previous needle loop after it is shed 20 from the looper and on the downward movement of the needle.

3. The combination with a needle, a needle bar, a thread guide carried thereby, a thread controller coöperating with said thread 25 guide on the needle bar, and a plurality of movable thread guides engaging said needle thread between the thread guide on the needle bar and the needle eye and a device for engaging the thread between the mov- 30 able thread guides.

4. The combination with a needle, a needle bar, a rotary shaft, a crank carried thereby, a link intermediate said crank and said needle bar, a thread arm carried by 35 said link, a plurality of thread guides carried by said arm, a stationary thread guide coöperating with said thread guides, a thread guide carried by said needle bar, and a thread controller coöperating with 40 the thread guide on said needle bar.

5. The combination with a presser bar, a needle, a needle bar, a thread guide carried thereby, a presser bar, a thread controller mounted on top of the head of the 45 machine, adjacent the upper end of the needle bar, said thread controller including a lever, having a thread guide at its forward end, an adjustable post forming a pivotal support for said lever and a link 50 connecting said lever to the presser bar.

6. The combination with a presser bar, a needle, a needle bar, a thread guide carried thereby, a presser bar, a thread controller mounted on top of the head of the machine 55 adjacent the upper end of the needle bar, said thread controller including a lever having a thread guide at its forward end, an adjustable post forming a pivotal support for said lever and a link connecting said le- 60 ver to the presser bar, needle thread controlling guides, and means for operating

the needle bar and said thread controlling guides.

7. In a sewing machine, a thread controlling device including in combination a movable member, two spaced thread guides carried thereby, a stationary thread guide, a second movable member, thread guides carried thereby, and engaging the thread upon opposite sides of the stationary thread guide 65 and in the space between said stationary thread guide and the first named movable guides, and means for moving said member, whereby the distance between the two first named spaced thread guides respectively 70 and the stationary thread guide is constantly changing.

8. In a sewing machine, a thread controlling device including in combination a stationary thread guide, a movable member, 80 thread guides carried thereby, and located upon opposite sides of said stationary guide, and moving in a vertical line, a second movable member and thread guides carried thereby, and located upon opposite sides of 85 said stationary thread guide, and moving in a direction at an angle to the path of movement of the first named movable thread guides.

9. In a sewing machine, a thread controlling device including in combination a stationary thread guide, a movable member, thread guides carried thereby, and located upon opposite sides of said stationary guide, and moving in a vertical line, a second movable member and thread guides carried 95 thereby, and located upon opposite sides of said stationary thread guide, and moving in a direction at an angle to the path of movement of the first named movable 100 thread guides, said second named thread guides also moving in opposite directions to each other.

10. A sewing machine comprising a thread controlling device including two 105 spaced thread guides, means for supporting and moving said thread guides at the same speed in the direction of a line passing through the guides, a stationary thread eyelet, thread eyelets on each side of said stationary eyelet, said eyelets being located between the two spaced thread guides, and means for moving the eyelets at each side of the stationary eyelet, whereby the same are given a differential movement relative 110 to said stationary eyelet.

In testimony whereof I affix my signature, in presence of two witnesses.
